CLAIM

The ornamental design for a roofing support system, as shown and described.

DESCRIPTION

FIG. 1 is a perspective view of a first embodiment of a roofing support system comprising the upper core member and an attached lower cover layer member comprising an elastomeric polymer foam; FIG. 2 is a top view thereof;

FIG. 3 is a bottom view thereof;

FIG. 4 is a left side view thereof;

FIG. 5 is a right side rear view thereof;

FIG. 6 is a front view thereof;

FIG. 7 is a rear view thereof;

FIG. 8 is a perspective view of a second embodiment of a roofing support system comprising an upper core member and an attached lower cover layer member comprising an elastomeric polymer foam;

FIG. 9 is a top view thereof;

FIG. 10 is a bottom view thereof;

FIG. 11 is a left side view thereof;

FIG. 12 is a right side rear view thereof;

FIG. 13 is a front view thereof; and,

FIG. 14 is a rear view thereof.

1 Claim, 10 Drawing Sheets
